UNITED STATES PATENT OFFICE.

JAMES W. BROWN, OF PADUCAH, KENTUCKY.

BRICK-MACHINE.

SPECIFICATION forming part of Letters Patent No. 349,477, dated September 21, 1886.

Application filed March 9, 1886. Serial No. 194,544. (No model.)

To all whom it may concern:

Be it known that I, JAMES W. BROWN, a citizen of the United States, residing at Paducah, in the county of McCracken and State of Kentucky, have invented certain new and useful Improvements in Brick-Machines, of which the following is a full, clear, and exact description, reference being had to the accompanying drawings, forming part of this specification, in which—

Figure 1 represents a front perspective view of a brick-machine embodying my improvements. Fig. 2 is a longitudinal sectional view of the same. Fig. 3 is a plan view of the upper cap or transverse plate. Fig. 4 is a detail view showing the movable boxing for the rear transverse shaft. Fig. 5 is a modification, to be hereinafter described.

My invention relates to reciprocating brick-machines; and the same consists in the construction and combination of devices hereinafter described and claimed.

To enable others skilled in the art to make and use my invention, I will now describe its construction and indicate the manner in which I have carried it out.

In the said drawings, A represents a suitable frame, in which the several operating mechanisms of my press are mounted. This frame 30 A consists, essentially, of two side pieces, between which is secured a rectangular or other shaped box, B, forming a chamber, in which the clay is thoroughly mixed, and from which it is discharged, as I shall hereinafter explain.

35 In the construction of this box or mixing-chamber I have found it desirable to have one or more of its sides removably secured, whereby the operator may adjust the agitator-arms, or clean the interior of the chamber, or free it

40 of stones or other incompressible substances, should such be found therein. A shaft, C, passes vertically through the center of the box, and through a suitable stuffing-box, c', and has secured thereon the arm or agitators 45 a, which are designed to engage the mass of clay and thoroughly mix the same, while on the lower end of the shaft and beneath the box is secured a gear-wheel, b, to which power is applied to rotate the shaft and arms. The 50 sides A of the frame are connected with each other by a transverse cap, D, the central por-

tion of which is open to permit the free passage of the clay as it leaves the hopper. This cap also furnishes a bearing for an internally-placed gear-wheel, c, it being confined within the cap by a plate, d, to which the hopper e is attached. This plate d is provided with standards f, in which is mounted the shaft g of the drum E, around which is passed the apron or carrier F, for delivering the clay to the hopper. The shaft g also carries a gear-wheel, h, which meshes with the gear-wheel c and rotates the same, whereby the plate d rotates on its central hub and enables the hopper to be turned to any angle, or to adjust itself with relation to the direction of the travel of the apron or carrier. This is an important feature in the construction of a brick-machine, as it permits the receiving end of the apron to be shifted from one point to another without causing a similar change in the position of the machine, as the hopper readily and automatically adjusts itself, so that the belt or apron will always register with the mouth of the hopper.

75 To hold the plate d to its seat against the cap, I employ small clips, 2 through which set-screws 3 may be passed, as shown.

At the rear of the machine the sides A of the frame are extended and provided with journal-boxes 5 and 6, for the transverse drive-shaft H, having secured thereon an eccentric, I, to which is attached, by a strap-connection, the pitman K, the forward end of which is attached to and operates the plunger L, as shown 80 in Fig. 2. This plunger L reciprocates within a chamber, 7, formed between the bottom plate, 8, of the box B, and a partition, 9, located immediately beneath said bottom, and during the reciprocating movements of the 85 press operates upon the clay as it passes through the opening 10 in the plate 8, and compresses said clay, in the manner I will hereinafter indicate.

Motion is imparted to the several operating 90 mechanisms through a drive-pulley, l, secured to one end of a transverse shaft, 11, journaled within the sides A. This shaft also carries pinions 12 and 13, the former of which meshes with the gear b on shaft C, and rotates said 100 shaft and arms or agitators, while the pinion 13 is located outside the frame and meshes

with an idle-gear, 14, on a shaft, *m*, as shown in Fig. 1.

The main shaft *H* has keyed or otherwise secured to one of its ends a large gear-wheel, 5 *M*, with which the gear 14 meshes, whereby the power of the pulley *l* is transmitted directly to the gear *M* through the medium of the gears 13 and 14, as before described.

The journal-box 6 adjacent to the gear-wheel *M* comprises a movable box or bearing, *n*, whereby said shaft may be moved horizontally to disengage the gear *M* with the gear 14. This important feature is necessary to relieve the press of the great strain that would be 15 brought upon it in the event of some hard incompressible substance finding its way to the chamber 7 during the movements of the plunger, and this feature is accomplished by means of a lever, *N*, fulcrumed at 15 to a lug, 16, 20 projecting from the frame, as shown in Fig. 1. The lever *N* is mounted on the shaft *H*, and extends to the front of the machine, so as to be within easy reach of the operator, who, when he discovers the presence of stones or other 25 hard substances, raises the lever *N*, which movement causes the box 6 to slide on its guide, carrying with it the shaft *H*, thereby moving the gear *M* from its engagement with the gear 14, and checking the further movement 30 of the eccentric *I* and plunger *K*.

The sides *A* at the front of the machine are provided with grooves *o*, in which vertically slides the shaper *P*, the upper portions of which are attached by links 17 to the oscillating arms 18, pivoted at or near the center of the frame, as shown in Fig. 1. This shaper *P* is provided with projecting lugs 19, between which slides a fender, 20, and between these lugs, in the body of the shaper, are 35 formed openings 21, whose configuration is approximately that of a brick, but whose dimensions are slightly less than the openings in the mold. It will be observed that the lower portion of these openings is provided with 40 knife-edges, the purpose of which is to sever the clay that has been forced into said openings in both shaper and mold by the plunger. By making the openings in the shaper slightly less than those in the mold it is evident the clay is 45 shaped and readily enters said mold without touching the sides of the same. The further movement of the plunger causes the clay to be forced into every portion of the mold and without disturbing the sand therein contained 50 when molding sanded brick. At the rear the arms 18 are connected by links 22 to a vertically-sliding frame, 23, having boxes 24 formed thereon, adapted to contain weights, whereby the shaper is counterbalanced and 55 caused to move upwardly to sever the clay, as I will presently describe. The frame 23 is provided with a projecting lug or lip, 25, and the shaft *H* has mounted thereon a cam-segment, 26, which, during the revolution of said 60 shaft, is designed to engage the lip 25 and raise the frame 23 and boxes 24 upwardly. This movement of the frame 23, through the agency

of the arms 18, affects the position of the shaper *P*, and causes said shaper to descend to permit the clay to be forced through the 70 openings 21 by the plunger *L*. As soon as the plunger has completed its forward movement, it will be found the segment has rotated until the point 27 has engaged the end of the lug 25, when a slight onward movement causes the 75 lug to be released from its engagement with the segment, when the weighted frame 23 immediately falls. This movement forces the shaper upward and severs the clay that had previously been forced through the openings 80 21.

Between the sides and at the lower portion of the frame *A* is pivotally secured a forked lever or receiver, *R*, the forward end of which carries a plate, 28, as shown in Figs. 1 and 2. 85 This receiver is preferably a counterbalanced frame, having at its rear an inclined lug or lip, 29, which is engaged by a cam, 30, secured to the segment 26, whereby during the rotation of the segment the cam 30 strikes against 90 the lip 29 and depresses the rear end of the lever or receiver *R*. The forward end of the lever is now raised, and the pallets which are placed upon the plate 28, and which receive the burned-out bricks, are brought directly 95 beneath the mold after the latter has received the clay and the same has been compressed. If it be desired to use the ordinary yard molds with bottoms, the front of the receiver may be elevated, when the lug 29 will not be affected 100 by the rotation of the segment.

The mold, *S*, used in the present instance is provided with openings corresponding with, but slightly larger than, the openings in the shaper, and has projecting ends 30, serving as 105 a shaft by which the mold may be made to describe arcs of circles in receiving and depositing the clay. One end of the shaft 30 is provided with a crank-arm, 31, having a wrist-pin projecting therefrom, and to which is attached the forward slotted end of a lever, *T*, fulcrumed upon a stud, 32, projecting from the frame *A*. This lever *T* is hinged or jointed at *r*, while its rear end, *s*, is weighted and cam-shaped, and is designed to be engaged by a pin, 110 *t*, projecting from the gear-wheel *M*, whereby when said pin engages the cam-shaped end *s* it raises said end. At the same time the forward end is depressed and the mold forced from a vertical to a horizontal position upon the plate 115 28 or interposed pallet. The rear end of the lever *T* is provided with a spring, *u*, the free end of which bears against the lever in front of its hinge-joint. This spring forms a yielding connection between the two parts of the lever, and permits the cam-shaped end to be raised by the pin without straining the lever should 120 there be any obstruction or derangement to the several parts of the machine, such as a rock in the shaper, &c.

In Fig. 5 is illustrated a mold-case which is designed to receive a wooden mold-frame for holding sanded brick.

The operation of the machine is substantially

as follows: The clay from the bank is delivered on the carrier F and deposited in the mixing-chamber through the hopper. From thence it passes into the chamber 7, where it is operated upon by the plunger. The shaper is then caused to descend by the segment 26 and lip 25 until its openings align themselves with the openings in the mold, the clay being forced through the openings 21 into the mold. The lever T, now being operated upon by the pin, forces the mold downward upon the pallet placed to receive the bricks, the receiver or lever R having in the meantime raised the plate 28 and pallet upward, so that the mold will find a seat upon the plate or its pallet.

By means of the construction herein described I am enabled to provide a compact substantial machine, and one in which the power applied to the several mechanisms is rendered more effective than in many of the machines now in use for similar purposes.

Having thus described my invention, what I claim as new, and desire to secure by Letters Patent, is—

1. In a brick-machine, a hopper mounted on a rotating plate and adapted to be automatically adjusted to different angles, substantially as herein described.

2. In a brick-machine, a cap or top plate having a rotating plate secured thereto, in combination with a hopper secured to said rotating plate and a drum and apron or carrier for automatically adjusting said plate and delivering the clay to the hopper, substantially as herein described.

3. In a brick-machine, the frames A, shaft C, and a box or receptacle, B, in combination with a cap or top plate, D, a plate, d, mounted to rotate on said shaft, an internally-placed gear-wheel, e, the drum E, supported on the rotating plate, the gear-wheel h, engaging the gear c, and the belt or carrier F, substantially as herein described.

4. In a brick-machine, a vertically-moving shaper having openings approximating the form and size of a brick, in combination with a weighted frame at the rear of the machine connected with and counterbalancing the shaper, substantially as herein described.

5. In a brick-machine, a vertically-moving shaper having openings formed therein, in combination with a frame connected with and counterbalancing the shaper, and a cam engaging a lug or lip on the counterbalanced frame and operating the shaper, substantially as herein described.

6. In a brick-machine, the sides A, having guides o, and the box B, in combination with a vertically-moving shaper having openings therein, the arms 18, pivoted to the sides, the links 17 and 22, and a frame having the weighted bars, substantially as herein described.

7. In a brick-machine, the sides A and the box B, in combination with a shaper, P, at the front of the machine, having openings formed therein, and a weighted frame at the rear of

the machine connected with and operating the shaper, substantially as herein described.

8. In a brick-machine, the sides A and box 70 B, in combination with the transverse shaft H, mounted in the rear of the frame, the cam-segment 26 on said shaft, the weighted frame 23, having a lug or lip, 25, and the shaper P, substantially as herein described. 75

9. In a brick-machine, the side pieces, A, and the box or receptacle B, in combination with the transverse shaft H, the cam-segment 26, the weighted frame 23, having a lug or lip, 25, projecting therefrom, the shaper P, connected with and operated by the segment and weighted frame, the eccentric I, mounted on the shaft H, the plunger L, and the pitman K, substantially as herein described.

10. In a brick-machine, the side pieces, A, and 85 the box or receptacle B, in combination with the transverse shaft H, the segment 26, having a cam, 30, formed thereon, the pivotally-secured lever or receiver R, having a lug, 29, and the plate 28 on the forward portion of 90 the lever, substantially as herein described.

11. In a brick-machine, the sides A and the box or receptacle B, in combination with a pivoted mold adapted to describe arcs of circles and to receive and deposit the clay, 95 and a mechanism comprising the pivoted lever T and its adjuncts, whereby the mold is automatically operated, substantially as herein described.

12. In a brick-machine, the side pieces, A, and 100 the box B, in combination with a vertically-moving shaper having a fender, 20, attached thereto, having a crank-arm, 31, a cam-lever, T, connected with said arm, the wheel M, having a pin engaging the said lever and operating the mold, and an oscillating mold, substantially as herein described. 105

13. In a brick-machine, the combination, with the side pieces, A, and box B, of the vertically-moving shaper having a fender, an 110 oscillating mold, a pivotally-secured vertically-moving lever or receiver, the transverse shaft H, having a segment mounted thereon, and a cam, 30, on the segment adapted to engage a lug on the lever, substantially as herein described. 115

14. In a brick-machine, the frame A, in combination with the transverse shaft H, the gears 13, 14, and M, a movable bearing for one end of the shaft H, and a lever, N, for forcing the 120 gear M from its engagement with the gear 14, substantially as herein described.

15. In a brick-machine, the sides A and box B, in combination with a transverse shaft H, the gear M, having a projecting pin, a jointed 125 and weighted lever, T, an oscillating mold having a crank-shaft engaged by said lever, and a spring, substantially as herein described.
